Philip C. Michel, Schenectady, New York, General Manager of the General Electric Company, has been elected President of the National Electric Light Association, and will preside at the meeting to be held in New York City, October 15-17, 1903. The election was held at the meeting of the Board of Directors of the Association, held at the Hotel Astor, New York, on September 23, 1903.

Application April 16, 1941, Serial No. 388,820

9 Claims. (Cl. 177—353)

My invention relates to circuits for discharge devices and concerns particularly counting and timing arrangements.

It is an object of my invention to provide an improved electrical impulse counter and frequency divider, as well as either a frequency indicator or timer.

A further object of my invention is to provide such arrangements, which operate independently of the time interval between impulses down to a lower limit fixed by the characteristics of discharge devices available, and which is adapted to cascading in stages and to variation of the scale or dividing factor for each stage.

In carrying out my invention in its preferred form I provide a plurality of electric discharge devices having anodes, cathodes, and control electrodes so connected as to form a series circuit when all of the discharge devices are conducting and having separate cathode resistors to ground. Suitable couplings between cathodes are provided to prevent series firing of all the tubes when an input signal is applied to the control electrodes, whereby one tube is ignited at a time, the first discharge device and its anode circuits being supplied by a source of anode voltage and each succeeding discharge device having the anode supplied by the voltage across the cathode resistor of the preceding discharge device. In this way the first impulse fires or ignites the first tube and raises the voltage across its cathode resistor sufficiently to ignite the second tube when the next impulse is received. Successive impulses ignite additional tubes so that the number of impulses which have been received is indicated by determining the number of discharge devices which are conducting. A connection is provided between the last discharge device and the first to extinguish the discharge in all of the devices when the last discharge device becomes conducting. A connection taken from the circuit of the last discharge device may be utilized to supply impulses to a second stage in which the number of impulses received is a fraction of the impulses supplied to the preceding stage. The dividing factor of each stage is determined by the number of discharge devices in the stage.

A better understanding of the invention will be afforded by the following detailed description considered in connection with the accompanying drawings, in which Fig. 1 is a circuit diagram of a counter circuit having a scale of 5 which may be employed as one stage of a multistage counter system; Figs. 2A and 2B are graphs repre-

senting the input and output voltages of the circuit represented in Fig. 1; Fig. 3 is a schematic diagram representing a cascading arrangement; Fig. 4 is a circuit diagram illustrating a modification of Fig. 1 using a vacuum type extinguishing tube; and Fig. 5 is a modification of Fig. 4 for a scale of 2. Those features of my invention which are believed to be novel and patentable are pointed out in the claims appended hereto.

In Fig. 1 there is illustrated a counter circuit which may be utilized independently as a counter for counting the remainder of any number of impulses divided by 5, and as a frequency divider for producing impulses one-fifth as great in number as the input impulses, or which may serve if desired as an intermediate stage 10 of a multistage system represented diagrammatically in Fig. 3. There is provided an input terminal 11 with a neutral terminal 12, which may be grounded, so that an input voltage signal may be applied between the terminals 11 and 12. There is an output terminal 13 and the output signal appears as a voltage between the terminals 12 and 13. A plurality of discharge devices T_1, T_2, T_3, T_4 , and T_5 is provided having electrodes designated by letter symbols with appropriate subscripts corresponding to those of the discharge devices. These electrodes include anodes A_1-A_5 , control electrodes CG_1-CG_5 and cathodes K_1-K_5 . I have obtained satisfactory results with discharge tubes having also shield electrodes designated by the symbol SG. The cathodes may be of the indirectly heated type. The discharge devices are of the type in which a discharge continues after an impulse of suitable voltage has been applied to the control electrode provided voltage is continually applied to the anode. Electric valves of the type commonly referred to as gaseous discharge tubes may be employed. Tubes of this type are also designated as vapor electric discharge tubes, ionic discharge tubes, and Thyratrons. However, I shall employ the term "gaseous discharge tube" and "gaseous discharge device" throughout the description and claims to refer to discharge devices of the type having the characteristics mentioned, regardless of their actual construction.

A source of anode voltage is provided and may be connected between the terminal B+ and the ground terminal 12. A plurality of current-conducting cathode impedances such as resistors R₁₈, R₁₇, R₁₆, R₁₅, and R₁₄ is connected in the cathode-to-ground circuits of the discharge tubes T₁, T₂, T₃, T₄, and T₅ respectively. The tubes also have

connections from the cathode of one to the anode of the next so that they may be considered as connected in series between the anode source B+ and the ground terminal 12. Substantially non-conductive coupling devices such as condensers C₁, C₂, C₃, C₄, and C₅ are connected between the input signal terminal 11 and the control electrodes CG₁ to CG₅ of the tubes T₁ to T₅.

The source of negative biasing voltage is connected between the bias terminal C- and the ground terminal 12. For connecting the negative bias terminal C- to the control electrodes a plurality of relatively low-conductance connections such as resistors R₁—R₅ of the order of a megohm is provided. In order to prevent the effective bias potential of the control electrodes from falling too far below the cathode potentials and injuring the discharge tubes, voltage divider circuits are preferably provided formed by connecting resistors R₆—R₁₀ between the control electrodes and cathodes of the tubes T₁—T₅ respectively, the resistors R₆—R₁₀ having smaller resistances than the resistors R₁—R₅ and the voltage dividers being formed by the series connections of the resistors. In the case of T₁ the voltage divided consists of the resistors R₁ and R₆ in series.

The arrangement is such that a discharge as initiated in tube T₁, which may be referred to as the initiating tube and the discharge is extinguished by the action of the tube T₅, which may be referred to as the extinguishing tube. The remaining devices T₂, T₃ and T₄ may be increased or reduced in number or may be omitted entirely according to the division factor desired between input and output signals, and these tubes if employed are referred to as intermediate tubes. Coupling condensers C₆, C₇, and C₈ are provided between the cathodes of the intermediate tubes T₂, T₃, and T₄ and the cathodes of the preceding tubes. Resistors R₁₁, R₁₂ and R₁₃ are included in the respective connections. The extinguishing tube T₅ has its anode A₅ connected to the cathode K₄ of the tube T₄ by means of a resistor R₁₄ and a condenser C₉ is connected between the anode A₅ and ground. The time constant of the circuit R₁₄, C₉ is made large enough so that, when the tube T₄ ignites, the rise of the anode potential of the extinguishing tube T₅ to the ignition level will be delayed until the control electrode CG₅ has dropped sufficiently negative to hold off conduction of the tube T₅.

The condensers C₆, C₇ and C₈ in the connections between the cathodes of the intermediate tubes and the preceding tubes have sufficient capacity to raise the cathode potential of a tube with its anode potential when the preceding tube fires in order to prevent firing of both tubes. For example, the capacity of the condenser C₆ is sufficiently large and the resistance of the resistor R₁₁ is sufficiently small in relation to the resistance of the resistor R₁₇, so that the potential of the cathode K₂ rises when the potential of anode A₂ is raised by the passage of current through the cathode resistor R₁₆; and the potential of the cathode K₂ remains high until the input signal disappears, whereby the potential difference between the electrodes A₂ and K₂ remains less than required to maintain an arc until the control electrode CG₂ is no longer at positive potential. The resistors R₁₁, R₁₂ and R₁₃ in the connections between the cathodes have such resistances as to limit the

anode currents in the intermediate discharge devices during discharge thereof and to permit gradual dissipation of the energy stored in each of the condensers C₆, C₇ and C₈ when the corresponding discharge tube ignites. For example, after a sufficient time delay the condenser C₆ becomes charged, the potential existing across the cathode resistor R₁₆. Then when the tube T₂ is ignited by the second input impulse, the resistor R₁₁ limits to a safe value the current discharging the condenser C₆ and flowing through the tube T₂.

For extinguishing the discharge in the initiating tube T₁ when the extinguishing tube T₅ is ignited, a relatively large condenser C₁₀ is connected between the cathode of the extinguishing tube T₅ and the cathode of the initiating tube T₁. The time constant of the circuit C₁₀, R₁₅ is made small enough so that the charging of the condenser C₁₀ (initiated by the firing of the tube T₁) will not hold the cathode of the extinguishing tube T₅ positive for such a long time as to prevent firing on each fifth impulse at the highest input pulse frequency to be used. The time constant of the circuit of the condenser C₉ discharging through T₅ into R₁₅ and through the condenser C₁₀ into the resistor R₁₆ effectively shunted by R₁₇, R₁₈, R₁₉, and R₂₀ is made large enough, however, to hold the cathode K₁ of the initiating tube T₁ positive until the initiating tube T₁ is deionized, and its control grid has fallen from the fifth impulse to a potential which prevents recurrence of conduction on that impulse.

The anode A₅ of the extinguishing tube T₅ may be employed as the output terminal if the circuit into which the output feeds is not such as to react objectionably upon the counter circuit and if an output impulse of reversed polarity is acceptable. However, I consider it advantageous to provide an isolating and coupling circuit which reverses the polarity from that of the anode A₅ to provide amplified output impulses of the same polarity as the input. The coupling circuit for the output may take the form of a discharge device T₆ with an anode A₆, a control electrode or grid G₆ and a cathode K₆. A coupling condenser C₁₁ may be connected between the anode A₅ and the control grid G₆ with a resistor R₂₀ interposed, and a gridleak resistor R₂₁ may be connected between the control electrode and the cathode. If the coupling circuit is to serve also as a polarity reversing circuit, an anode resistor R₂₂ is advantageously connected between the voltage source terminal B+ and the anode A₆ and the tube T₆ is advantageously of the continuous control or vacuum type, sometimes called a "hard tube." For restoring all of the tubes to the non-conducting condition a reset switch 14 may be connected between the anode voltage source B+ and the anode A₁ of the initiating tube T₁.

For conveniently indicating which of the tubes is the last to become conducting, voltage responsive indicators, preferably of the zero or low current drain type such as neon discharge tubes, are connected between the anodes and cathodes of the tubes T₁—T₅, and they carry the scale numerals 0, 1, 2, 3, and 4, respectively, to indicate the number of impulses received in a manner which will be explained hereinafter.

It will be understood that if discharge devices of the indirectly heated cathode type are employed, a suitable source of heater current, not shown, is provided, and this source may be held

at a positive potential by means of a tap on a voltage divider, not shown, connected across the anode voltage source to prevent excessive potential difference between the heaters and the cathodes.

The manner in which the indicators 0, 1, 2, 3, and 4 indicate the number of impulses which have been received will be apparent from a consideration of the manner of operation of the circuit. Before any impulses have been received and when none of the tubes are conducting, the full voltage of the anode source B+ to ground appears across the anode and cathode of the initiating tube T₁. Consequently, voltage also appears across the zero-indicating device 0. The fact that this device is energized or lighted indicates that the count thus far is zero. The other indicators 1, 2, 3, and 4 are dark for the reason that these remaining tubes obtain their voltage from the potential drop across the first cathode resistor R₁₈ which at this time carries no current and therefore has a zero potential drop. When the first impulse is applied to the input terminal 11 the control electrodes of all five discharge tubes are driven positive to overcome the negative bias of the source C-. Accordingly, the initiating tube T₁ becomes conducting. The other tubes do not become conducting, however, because they have no anode voltage applied. As current begins to flow in the cathode resistor R₁₈ it raises the potential of the anode A₂ of the first intermediate tube T₂ but the capacitative coupling C₈ causes the potential of the cathode K₂ to rise with that of the anode A₂, thus preventing ignition of the first intermediate tube T₂. Since the input impulses are of short time duration, the positive voltage impulse applied to the control electrode CG₂ will have disappeared before the potential of the cathode K₂ has fallen sufficiently below that of the anode A₂ for ignition of T₂. The rate at which the potential of the cathode K₂ falls to zero is determined by the time required for the condenser C₈ to charge through the resistors R₁₁ and R₁₇. Potential appearing between A₂ and K₂ causes the indicator 1 to light, and at the same time the reduction of potential between A₁ and K₁, due to conduction of T₁, extinguishes the indicator 0.

When the next input signal is received the control electrodes are again driven positive and this time the first intermediate tube T₂ ignites because its anode is energized by the voltage across the resistor R₁₁. The condenser C₈ thereupon discharges through the tube T₂ but the discharging current is limited by the resistor R₁₁ to protect the tube. Since the tubes T₁ and T₂ are now both conducting the indicating devices 0 and 1 are both shunted so that they do not light up. Voltage appears, however, across the indicating device 2 connected across the tube T₃ since there is now a voltage drop across the cathode resistor R₁₇. Ignition at this time of the tube T₃ was prevented by the coupling C₇ in the same manner as previously discussed.

Subsequent impulses will ignite the additional tubes one at a time. Each time the number of impulses received will be indicated by which one of the indicating devices 0-4 is energized, all but one of these being deenergized for the reasons explained. When the fourth impulse is received the voltage across the cathode resistor R₁₉ rises as in the previous case. However, the extinguishing tube T₅ is prevented from firing by reason of the time delay required for the condenser C₉ to be charged sufficiently to raise the anode potential 75

of the tube T₅ before the positive impulse has disappeared from the control electrodes.

When the last impulse is received, in this case the fifth impulse (or any multiple thereof), the extinguishing tube T₅ becomes conducting and the potential rises across the cathode resistor R₁₅. The relatively high capacity connection between the cathode K₅ and the cathode K₁ momentarily raises the potential of the cathode K₁ above that of the anode T₁ so as to extinguish the discharge in the initiating tube T₁. Before the condensers C₉ and C₁₀ have discharged to lower the cathode potential of the initiating tube T₁, that tube has become deionized so that current therein ceases and the voltage drop across the resistor R₁₈ falls to zero. The ignition of the remaining tubes T₂-T₅ has thereby also been extinguished. The circuit is thus restored to its initial condition and the same action may be repeated indefinitely. After any number of impulses the indication last produced will be retained if no further impulses are received, because the circuit is stable and does not depend upon the retention of charge by a condenser.

25 It will be understood that my invention is not limited to the use of circuit elements having specific numerical values of constants nor to the use of particular classes of electric discharge devices. I have found, however, that satisfactory results may be obtained by employing gas tetrodes of the construction designated as 2051 for the gaseous discharge devices T₁ to T₅, by employing a vacuum type triode consisting of half a tube known by the designation 6N7 to form the coupling discharge device T₆ and by using numerical values of circuit constants indicated in the following tabulation:

40	C ₁ -C ₅	micromicrofarads	40
	C ₆ -C ₈	microfarad	.006
	C ₉	do	.02
	C ₁₀	do	.05
30	C ₁₁	micromicrofarads	20
	R ₁ -R ₅	megohms	2
	R ₆ -R ₁₀	do	0.5
45	R ₁₁ -R ₁₃	ohms	1,000
	R ₁₄	do	10,000
	R ₁₅ -R ₁₉	do	50,000
	R ₂₀	megohms	0.5
50	R ₂₁	do	0.15
	R ₂₂	ohms	15,000
	B+	volts	300
	C-	do	-45

55 The indicators 0 to 4 may be neon tattelites with one-half megohm series resistors.

Utilizing the tube classifications as specified, when using input voltage signals of 20 volts or more, the input signal wave may be represented by the graph of Fig. 2A where the duration of the positive signal impulses may be 50 microseconds or less. The interval between input impulses may be any value greater than 500 microseconds. The limiting values depend of course upon the tube characteristics. Employing five tubes in order to obtain a scale of five as shown in Fig. 1, the output voltage signal is represented by Fig. 2B, where the voltage is approximately 130 volts with the circuit constants specified. The duration of the output signal impulse depends only upon the magnitudes of the elements in the coupling circuit, viz: the condenser C₁₁ and resistors R₂₀ and R₂₁.

As already mentioned, the number of intermediate tubes T₂ and T₄ may be changed, or they may be eliminated entirely in order to

change the division factor between the number of input and output signals. For example, if the intermediate tube T_3 is removed together with all of the apparatus within the dotted rectangle 15, the number of output impulses will be one-fourth the number of input impulses. If all three tubes T_2 , T_3 and T_4 are omitted, together with the other elements corresponding to those within the dotted rectangle 15, the scale-of-two counter is formed having an initiating tube T_1 and the extinguishing tube T_5 . If a decimal system of counting is desired, five additional tubes may be added to the circuit of Fig. 1 to form a scale-of-10 counter and divider. Alternatively, the circuit shown may be cascaded with a scale-of-two impulse counter or divider to produce a division by 10. Any number of such circuits may be cascaded as desired or the impulse counter 10 may be cascaded with impulse counters and dividers of other electrical or mechanical types according to the anticipated frequency in each stage of the counting system, each stage effecting a division according to its scale.

I have referred to my circuit particularly in connection with its use as a counter of impulses or as a divider of the frequency or the number of impulses. However, the circuit may be employed as a timer if the input signals are supplied from a constant frequency source, or the circuit may be used as a frequency meter if the impulses are supplied for a fixed time duration.

In the arrangement illustrated in Fig. 1, premature ignition of the intermediate tubes is prevented by condensers C_6 , C_7 , and C_8 which are each connected between the cathode of an intermediate tube and the cathode of the preceding tube. Premature ignition of the extinguishing tube T_5 when the preceding tube ignites is prevented, however, by a condenser between the anode of the extinguishing tube and the ground connection 12 with the resistor R_{14} interposed in the anode lead of the extinguishing tube T_5 . My invention is not limited, however, to having only the extinguishing tube connected in this manner for prevention of premature ignition. The arrangement illustrated has the advantage, nevertheless, that there is less condenser energy to be dissipated when the extinguishing tube T_5 becomes conducting for the reason that the condensers C_6 , C_7 , and C_8 are discharged before the tube T_5 becomes conducting.

Although I have illustrated and described a counter or divider circuit in which the last stage tube, that is, the extinguishing tube T_5 is of the gaseous type, it is to be understood that my invention is not limited to the precise arrangement thus far described. Since the extinguishing tube T_5 is not required to remain conducting after the voltage impulse which fires it disappears, it is not necessary that the extinguishing tube be of the gaseous or ionic discharge type. A so-called hard tube or vacuum tube may also be employed.

If desired, the extinguishing tube may take the form of a four-element vacuum discharge device having a second grid or positive electrode referred to as a screen grid, as illustrated in Fig. 4. In Fig. 4 the gaseous discharge device T_5 is replaced by a vacuum tube 17 having an anode 18 directly connected to the anode voltage source B_+ and having three other electrodes connected as a triode in the same manner as the anode, control electrode and cathode of the gaseous discharge tube shown in Fig. 1. The

vacuum tube 17 may be of the type designated as 6L6 for example. The vacuum tube 17 has a screen grid 19 which may be considered either as a second control electrode or a second positive electrode, corresponding to the anode of a triode and the positive electrode 18 is connected through the resistor R_{14} to the cathode of the preceding tube as in Fig. 1. The vacuum tube 17 has also a control electrode CG_5 and a cathode K_5 corresponding to the electrodes bearing the same reference numerals in Fig. 1. It will be understood that the negative bias applied to the control electrode CG_5 of the tube 17 should be so chosen as to give the best results with this type of tube and the relative magnitudes of the potentiometer resistors R_7 and R_8 are so chosen as to give the desired negative bias. To simplify the drawing, some of the intermediate stages have been omitted in Fig. 4 and are indicated simply by the dotted rectangle 20. If these are omitted, the arrangement of Fig. 4 becomes a scale-of-three counter.

In considering the electrodes 19, CG_5 and K_5 as a triode, the operation of the circuit of Fig. 4 is the same as that of Fig. 1. When the first positive voltage impulse is applied to the input electrode 11, the initiating tube T_1 , a gaseous tube is fired. This operation short-circuits the neon tube 1, causing the light to go out and the voltage drop across the cathode resistor R_{18} applies voltage to the anode A_2 of the intermediate tube T_2 and also applies voltage to the neon tube 1. The neon tube 1 is thus illuminated to indicate that the first impulse has been received. On the application of a second voltage impulse to the input terminal 11, the intermediate tube T_2 fires and voltage appears across the resistor R_{17} . Assuming the additional stages 20 have been omitted, the voltage is then applied through the resistor R_{14} to the screen grid 19 of the vacuum tube 17 and to the neon tube which is connected between the screen grid 19 and the cathode of the vacuum tube 17. The vacuum tube 17 is prevented from firing, however, by reason of the time delay produced by the connection of the condenser C_9 between the screen grid 19 and the terminal 12. This holds the screen grid 19 at a sufficiently low potential momentarily to prevent a discharge in the tube 17 until the impulse applied to the terminal 11 has fallen to zero. Gradually the potential of the screen grid 19 rises to the value of the voltage drop across the cathode resistor of the preceding tube and thus the vacuum tube 17 is primed for operation upon reception of the next impulse applied to the input terminal 11. When the next impulse is received it raises the potential of the control electrode CG_5 and causes the tube 17 to fire. The screen grid 19 carries relatively little current and serves to discharge the time delay condenser C_9 . However, the anode 18 supplies the principal portion of the discharge current which flows through the cathode resistor R_{18} , causing a sudden rise in the potential of the cathode K_5 . This potential is transmitted to the cathode K_1 of the initiating tube through the condenser C_{10} , and the initiating tube T_1 is extinguished in the same manner as explained in connection with Fig. 1.

The circuit of Fig. 4 may be converted to a scale-of-two-counter in the same manner as the circuit of Fig. 1 by omitting also the intermediate tube T_2 with its associated circuit elements C_6 , R_{11} , R_{17} , neon tube 1, coupling condenser C_2 , potentiometer resistors R_7 and R_8 . The resistor

R_{14} will then be connected directly between the cathode K_1 and the positive electrode of the triode portion of the tube 17, that is, to the screen grid 19.

However, the use of a hard tube for the screen grid for the extinguishing function permits a further simplification in the case of a scale-of-two-counter. As illustrated in Fig. 5 the time delay elements R_{14} and C_9 may be omitted in the simplified arrangement illustrated in Fig. 5. Since the screen grid 19 is not required to supply appreciable current for the discharge of the tube 17, a condenser such as the condenser C_9 is not required between the screen grid 19 and the ground connection for supplying energy to produce a strong discharge in the vacuum tube 17. The energy in this case comes from the anode voltage source B_+ which is connected to the anode 18. There is also no need for the elements R_{14} and C_9 to introduce time delay in the application voltage to the screen grid 19 when the tube T_1 fires because the condenser C_{10} connected between the cathodes of the two tubes causes the potential of the cathode K_5 of the tube 17 to rise momentarily when the initiating tube T_1 fires, thus preventing sufficient potential difference between the screen grid 19 and the cathode K_5 to permit premature ignition of the tube 17.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. A counter circuit comprising a plurality of gaseous discharge devices including an initiating discharge device, an extinguishing discharge device, and one or more intermediate discharge devices, each discharge device having an anode, a cathode and a control electrode, an input terminal adapted to have electrical impulses to be counted applied thereto, a ground terminal, an output terminal, an anode voltage source terminal, a negative bias voltage source terminal, a plurality of low-current-drain indicators equal in number to the said gaseous discharge devices each connected between the anode and the cathode of one of said discharge devices, a plurality of cathode resistors each connected between one of said cathodes and said ground terminal, substantially non-conductive couplings between said input terminal and said control electrodes, low conductance connections between said bias voltage terminal and said control electrodes, a connection between said anode voltage terminal and the anode of said initiating discharge device, a plurality of connections each between the cathode of one discharge device and the anode of the next whereby all of the discharge devices are connected in series, the initiating discharge device being the first and the extinguishing discharge device being the last in the series, a resistor being included in the connection between the anode of the extinguishing discharge device and the cathode of the preceding discharge device, a plurality of connections each including resistance and capacitance in series between the cathode of each intermediate discharge device and the cathode of the preceding discharge device in the series, a relatively large condenser connected between the cathodes of the initiating and extinguishing dis-

charge devices and a voltage-reversing coupling circuit having an input side connected between the anode of the extinguishing discharge device and the ground terminal and having an output side connected between the said output terminal and ground, whereby the anode-cathode circuit of the initiating discharge device is energized from said anode voltage supply terminal and each of the other discharge devices is energized by the voltage across the cathode resistor of the preceding discharge device in the series, and each electrical impulse applied to the input terminal fires the first discharge device in the series which is not already conducting until the extinguishing discharge device is caused to become conducting whereupon all of the discharge devices are extinguished, each of said indicating devices thus being energized only when the discharge device across which it is connected has voltage applied to the anode but is not conducting so that the number of impulses is indicated by which one of the indicating devices is energized.

2. A counter circuit comprising a plurality of gaseous discharge devices, each discharge device having an anode, a cathode and a control electrode and an input terminal adapted to have electrical impulses to be counted applied thereto, a ground terminal, an anode voltage source terminal, a negative bias voltage source terminal, a plurality of cathode resistors each connected between one of said cathodes and said ground terminal, substantially non-conductive couplings between said input terminal and said control electrodes, low conductance connections between said bias voltage terminal and said control electrodes, a connection between said anode voltage terminal and the anode of the first of said discharge devices, connecting means between the cathode of any discharge device and the anode of the next whereby the discharge devices are connected in series, a resistor being included in the connecting means between the anode of the last discharge device and the cathode of the preceding discharge device, a condenser connected between the anode of said last discharge device and said ground terminal, substantially non-conductive coupling means between the cathode of each discharge device and the cathode of the discharge device following it including such coupling means between the last discharge device and the first, but excluding such coupling means between the last discharge device and the one preceding it other than the first, whereby the anode-cathode circuit of the first discharge device is energized from said anode voltage supply terminal and any other discharge device is energized by the voltage across the cathode resistor of the preceding discharge device in the series and each electrical impulse applied to the input terminal fires the first discharge device in the series which is not already conducting until the last discharge device is caused to become conducting whereupon the entire series of discharge devices is extinguished.

3. A counter circuit comprising a plurality of gaseous discharge devices including an initiating discharge device, an extinguishing discharge device and one or more intermediate discharge devices, each discharge device having an anode, a cathode and a control electrode, an input terminal adapted to have electrical impulses to be counted applied thereto, a ground terminal, an anode voltage source terminal, means for biasing the control electrodes of said discharge devices to non-conductive condition, a plurality of voltage responsive indicators each connected be-

tween the anode and the cathode of one of the discharge devices, a plurality of cathode resistors each connected between one of said cathodes and said ground terminal, substantially non-conductive couplings between said input terminal and said control electrodes, a connection between said anode voltage terminal and said initiating discharge device, a plurality of connections each between the cathode of one discharge device and the anode of the next whereby all of the discharge devices are connected in series, the initiating discharge device being the first and the extinguishing discharge device being the last in the series, means interposed between the circuit of each discharge device and the following one to maintain the potential difference between the anode and cathode of the following discharge device substantially unchanged momentarily, means interposed between the circuit of the extinguishing discharge device and the initiating discharge device to cause a change in potential in the same direction to take place momentarily in the cathodes of both said discharge devices when the extinguishing discharge device becomes conducting, whereby the anode-cathode circuit of the initiating discharge device is energized from said voltage supply terminal and each of the other discharge devices is energized by the voltage across the cathode resistor of the preceding discharge device in the series, and each electrical impulse applied to the input terminal fires the first discharge device in the series which is not already conducting until the extinguishing discharge device is caused to become conducting whereupon all of the discharge devices are extinguished, each of said indicating devices thus being energized only when the discharge device across which it is connected has voltage applied to the anode but is not conducting so that the number of impulses is indicated by which one of the indicating devices is energized.

4. A counter circuit comprising a pair of gaseous discharge devices referred to as an initiating discharge device and an extinguishing discharge device, each discharge device having an anode, a cathode and a control electrode, an input terminal adapted to have electrical impulses to be counted applied thereto, a ground terminal, an output terminal operatively connected to the anode of the extinguishing discharge device, an anode voltage source terminal, a negative bias voltage source terminal, a pair of cathode resistors each connected between one of said cathodes and said ground terminal, substantially non-conductive couplings between said input terminal and said control electrodes, low conductance connections between said bias voltage terminal and said control electrodes, a connection between said anode voltage terminal and the anode of said initiating discharge device, a resistor connected between the cathode of the initiating discharge device and the anode of the extinguishing discharge device whereby the discharge devices are connected in series, a relatively large condenser between the cathodes of the initiating and extinguishing discharge devices and a time delay condenser connected between the anode of the extinguishing discharge device and the ground terminal, whereby the anode-cathode circuit of the initiating discharge device is energized from said anode voltage supply terminal and the extinguishing discharge device is energized by the voltage across the cathode resistor of the initiating discharge device and suc-

cessive electrical impulses applied to the input terminal first fire the initiating discharge device and then the extinguishing discharge device with the ignition of the extinguishing discharge device simultaneously raising the cathode potential of the initiating discharge device by the capacitive coupling between cathodes to extinguish the discharge in both devices.

5. A counter or divider comprising a plurality of gaseous discharge devices and having an anode, a cathode and a control electrode, an input terminal adapted to have electrical impulses to be counted applied thereto, a ground terminal, an anode voltage source potential, means for holding the control electrode potential sufficiently low for normally preventing ignition of the discharge devices, a plurality of current conducting cathode impedances each connected between one of said cathodes and said ground terminal, coupling elements for maintaining the potential difference between anode and cathode of any discharge device substantially unchanged momentarily during ignition of the preceding discharge device, a connection between said anode voltage terminal and the anode of the first of said discharge devices, connecting means between the cathode of any discharge device and the anode of the next for connecting the discharge devices in series, and means for momentarily fixing the potential difference between the cathodes of the first and last discharge devices during ignition of the last discharge device, whereby the anode-cathode circuit of the first discharge device is energized from the anode voltage supply terminal and any other discharge device is energized by the voltage across the cathode impedance of the preceding discharge device in the series and each electrical impulse fires the first discharge device in the series which is not already conducting until the last discharge device is caused to become conducting and to raise the cathode potential of the first discharge device for extinguishing all of the discharge devices.
6. A counter or divider circuit comprising a plurality of discharge devices each having a positive electrode, a cathode and a control electrode, one of said discharge devices designated as the last being referred to as an extinguishing discharge device, the remainder of the discharge devices being of the gaseous discharge type only, an input terminal coupled to the control electrodes and adapted to have electrical impulses applied thereto, a ground terminal, a positive electrode voltage source terminal, means for holding the control electrode potentials sufficiently low for normally preventing current conduction by the discharge devices, a plurality of current-conducting cathode impedances each connected between one of said cathodes and said ground terminal, coupling elements for maintaining the potential difference between the positive electrode and the cathode of any discharge device substantially unchanged momentarily during ignition of the preceding discharge device, a connection between said positive electrode voltage source terminal and the positive electrode of the first of said discharge devices, connecting means between the cathode of any discharge device and the positive electrode of the next for connecting the discharge devices in series, with the said extinguishing discharge devices being the last in the series, and means for momentarily fixing the potential difference between the cathode of the extinguishing discharge device and the

first discharge device in the series during ignition of the extinguishing discharge device whereby the positive electrode to cathode circuit of the first discharge device is energized from the positive electrode voltage supply terminal and any other discharge device has voltage supplied by the potential difference in the cathode impedance of the preceding discharge device in the series, and each input impulse fires the first discharge device in the series which is not already conducting until the extinguishing discharge device is caused to become conducting to raise the cathode potential of the first discharge device for extinguishing all of the discharge devices.

7. A circuit comprising an initiating discharge device of the gaseous discharge type and an extinguishing discharge device, each discharge device having a positive electrode, a cathode and a control electrode, an input terminal adapted to have electrical impulses to be counted applied thereto, a ground terminal, a positive electrode voltage source terminal, means for holding the control electrode potentials sufficiently low for normally preventing current conduction by the discharge devices, couplings between said input terminal and said control electrodes, a connection between said positive electrode voltage source terminal and the positive electrode of the said initiating discharge device, a connection between the cathode of the initiating discharge device and the anode of the extinguishing discharge device whereby the discharge devices are connected in series, a pair of cathode impedances each connected between one of said cathodes and said ground terminal, and a relatively large condenser connected between the cathodes, whereby the positive electrode to cathode circuit of the initiating discharge device is energized from said positive electrode voltage source terminal and the extinguishing discharge device has voltage applied between the positive electrode and cathode by the potential difference across the cathode impedance of the initiating discharge device, and successive electrical impulses applied to the input terminal first fire the initiating discharge device and then the extinguishing discharge device with the ignition of the extinguishing discharge device simultaneously raising the cathode potential of the initiating discharge device by the capacitive coupling between cathode to extinguish the discharge in both devices.

8. A circuit comprising a plurality of discharge devices including an initiating discharge device and an extinguishing discharge device, the extinguishing discharge device being of the vacuum type having an anode, an auxiliary positive electrode, a control electrode and a cathode, except for the extinguishing discharge device said discharge devices being of the gaseous discharge type each having a positive electrode, a control electrode and a cathode, an input terminal adapted to have electrical impulses to be counted applied thereto, a ground terminal, a positive electrode voltage source terminal, substantially non-conducting couplings between said input terminal and said control electrodes, means for holding the control electrode potentials sufficiently low for normally preventing appreciable current conduction by the discharge devices, a plurality of current conducting cathode impedances each connected between one of said cathodes and said ground terminal, coupling elements for maintaining the potential difference between the positive electrode and cathode of any dis-

charge device substantially unchanged momentarily during ignition of the preceding discharge device, a connection between said positive electrode voltage source terminal and the positive electrode of the initiating discharge device, connecting means between the cathode of any discharge device and the positive electrode of the next for connecting the discharge devices in series with the initiating device first in the series and the extinguishing discharge device last, the extinguishing discharge device being considered as a triode in said series circuit with the auxiliary positive electrode serving as the positive electrode of the triode, and means for momentarily fixing the potential difference between the cathodes of the first and last discharge devices, and a connection between the positive electrode voltage source terminal and the anode of the extinguishing discharge device, whereby the positive electrode to cathode circuit of the first discharge device is energized from the positive electrode voltage source terminal and any other discharge device except the extinguishing discharge device is energized by the voltage across the cathode impedance of the preceding discharge device in the series, the extinguishing discharge has its anode energized by said positive electrode voltage source terminal and its auxiliary positive electrode energized by the voltage across the cathode impedance of the preceding discharge device in the series, and each electrical impulse fires the first discharge device in the series which is not already conducting until the extinguishing discharge device is caused to become conducting and to raise the cathode potential of a first discharge for extinguishing all of the discharge devices.

9. A circuit comprising an initiating discharge device of the gaseous discharge type having an anode, a cathode, and a control electrode, an extinguishing discharge device of the vacuum type having an anode, an auxiliary positive electrode, a control electrode and a cathode, an input terminal adapted to have electrical impulses to be counted applied thereto, a ground terminal, an anode voltage source terminal connected to said anodes, a pair of cathode impedances each connected between one of said cathodes and said ground terminal, substantially non-conducting couplings between said input terminal and said control electrodes, means for holding the control electrode potentials sufficiently low for normally preventing appreciable current conduction by the discharge devices, a connection between the cathode of said initiating discharge device and the auxiliary positive electrode of the extinguishing discharge device, and a condenser connected between the cathodes of the discharge devices, whereby the anode-cathode circuits of the discharge devices are supplied by said anode voltage source and the auxiliary positive electrode to cathode circuit of the extinguishing device is supplied by the potential difference in the cathode impedance of the initiating discharge device when the initiating discharge device is conducting, and whereby successive electrical impulses applied to said input terminal fire the initiating discharge device and then the extinguishing discharge device with the ignition of the extinguishing discharge device simultaneously raising the cathode potential of the initiating discharge device by the capacitive coupling between the cathodes to extinguish the discharge in both devices.
